SAFETY MECHANISM FOR FIREARMS

Filed August 27, 1925

Fig. 5.

Fig. 4.

Inventor
Louis P. Smith

Attorney
J. H. Bryant

UNITED STATES PATENT OFFICE.

LOUIS P. SMITH, OF ITHACA, NEW YORK.

SAFETY MECHANISM FOR FIREARMS.

Application filed August 27, 1925. Serial No. 52,899.

To all whom it may concern:

Be it known that I, LOUIS P. SMITH, a citizen of the United States of America, residing at Ithaca, in the county of Tompkins and State of New York, have invented certain new and useful Improvements in Safety Mechanism for Firearms, of which the following is a specification.

This invention relates to new and useful 10 improvements in safety mechanism for firearms.

The primary object of the invention is the provision of safety mechanism for firearms of the break-down type, wherein the moving 15 of the barrel locking member to an unlocked position will cause the trigger or triggers to be locked by the safety mechanism, which mechanism will remain inactive or in its locked position, even after the barrel has 20 been closed and locked, until manually released.

A further object of the invention is the provision of a novel form of connection between the barrel lock actuating member and 25 the trigger engaging and holding member.

Other objects and advantages of the invention will be apparent during the course of the following description.

In the accompanying drawing forming a 30 part of this specification and in which like numerals are employed to designate like parts throughout the same,

Figure 1 is a side elevational view of the safety mechanism embodying this invention 35 properly mounted within the frame portion of a fire arm,

Figure 2 is a transverse sectional view of the barrel lock actuating member with the safety mechanism setting pin carried thereby 40 and shown in top plan,

Figure 3 is a detail plan view of a push bar employed in connection with the safety mechanism,

Figure 4 is a top plan view of a safety 45 button retaining spring which also functions to operatively connect the button with the push bar shown in Fig. 3, and

Figure 5 is an end elevational view of the spring member shown in Fig. 4.

50 In the drawing, wherein for the purpose of illustration is shown a preferred embodiment of this invention, the numeral 5 designates the frame portion in its entirety which has journaled in the upper portion thereof 55 a post 6 flattened at its opposite sides, as designated by the numeral 7 in Fig. 2.

Straddling this flattened portion of the post 6 is a yoke member 8 which is operatively connected to the barrel locking bolt 9. This yoke 8 is retained in its operative position by means of the pin 10 which has the laterally projecting cylindrical head 11, as best shown in Fig. 2. The top and bottom tangs of the frame 5 are connected by the bolt 12.

In Fig. 3 there is shown in detail a push bar which includes the elongated body portion 13 having the longitudinally extending slot 14 formed intermediate its ends. The forward end of this push bar body 13 carries a fork 15 having a laterally extending declining arm 16 carried by one side thereof which is provided with a rearwardly bent end portion 17 that terminates inwardly of the outer ends of the side portions of the fork 15 and is provided with a depending lug 18 located in a plane extending transversely to the axis of the body portion of the push bar.

By inspecting Fig. 1, it will be seen that this push bar is arranged with the post 6 received within the fork 15 and with the rearwardly bent end 17 resting upon the cylindrical head 11 of the pin 10. The depending lug 18 is further illustrated as bearing against the rear face of the head 11. The slotted portion 14 of the push bar receives the tang bolt 12 and permits the said push bar to move in respect thereto. The rear end of the body portion 13 of this push bar is provided with a longitudinally extending finger 19 which forms the shoulders 20 on this end of the said push bar.

In Figs. 4 and 5 there is shown a spring member including a tapering body portion 21 having an elongated slot 22 formed therein, as best illustrated in Fig. 4. The rear end 23 of this body portion 21 is bent upwardly and downwardly into an inverted V-formation, which portion of the spring member will be described in connection with its function at a later point in the description. The forward end of this spring member 21 is provided with an upturned flange 24 which is transversely slotted at 25, see Fig. 5, and is provided with an inwardly turned lug 26 at its outer edge which overlies the body portion 21 of the spring member.

In Fig. 1 this spring member is illustrated as having the finger 19 of the push bar projecting into the slot 25 while the slot 22 receives the forked portion 27 of the safety

- button 28. This forked portion 27 is provided with a laterally projecting pin 29 which underlies the body portion 21 of the spring member, as shown. It will be understood that this spring member, in bearing against the inner face of the upper tang of the gun frame 5 and the upper face of the pin 29, will retain the fork 27 within the slot 30 formed in the upper tang.
- 10 This upper tang is provided with a recess 31 which is intended to receive a danger signal of any desired type which will be exposed when the safety button 28 is in the position illustrated in Fig. 1, i. e., when the
- 15 fork 27 is permitted to be arranged at the forward end of the slot 30. The under face of this upper tang is provided with a series of spaced notches 32 into which the inverted V-shaped end 23 of the spring member projects for aiding in holding the spring member, the safety button 28, and the push bar in either of two operative positions. This safety mechanism further includes an angular lever 33 which is pivoted to the lugs 34
- 20 carried by the lower tang of the gun frame. The upstanding arm of this angular lever projects between the sides of the fork 27 while the opposite end portion is received within a cavity or notch 35 formed in the
- 25 pivoted bolt 36 which is provided with a laterally projecting pin 37 that is intended to be moved into engagement with the upper edge 38 of the heel portions of the triggers 39 for preventing operation of the triggers.
- 30 The operation of this safety mechanism may be described as follows:—
- Upon rotating the post 6 in a counter-clockwise direction when viewed from above, the yoke 8 will be actuated for rotating the
- 35 barrel locking bolt 9 to release the barrel. This movement of the post 6 will cause the cylindrical head portion 11 of the pin 10 to move rearwardly in an arcuate path. This rearward movement of the head of the pin
- 40 10 will cause the push bar 13 to be moved longitudinally rearwardly of the frame, due to the engagement of the head 11 with the depending lug 18 of the push bar. This rearward movement of the push bar will
- 45 cause the shoulders 20 to engage the opposite sides of the upturned flange 24 of the spring member for moving this latter member rearwardly of the gun frame. This rearward movement of the spring member will cause
- 50 the fork 27 and the button 28 to travel rearwardly through the slot 30, which rearward movement will cause the lever 33 to pivot for rocking the bolt 36 upon its fulcrum for shifting the pin 37 into a position to engage
- 55 the surfaces 38 of the triggers 39. When the post 6 is returned to the position illustrated in Figs. 1 and 2, the head 11 of the pin 10 will return to its truly laterally extending
- 60 position, but will leave the push bar and its connected members into their shifting,

trigger-locking position. It will now be understood that the barrel is locked into its breech closing position and the safety mechanism is still functioning to retain the triggers 39 against movement. To unlock or release these triggers, the safety button 28 should be moved forwardly for causing the fork 27 to engage the forward end of the slot 22 in the spring member for moving this latter member toward the post 6. This movement of the spring member will cause the push bar to be returned to the position illustrated in Fig. 1. The angular lever 33 will also be pivoted for rocking the bolt 36 into the position illustrated in Fig. 1 wherein the triggers 39 will be free to operate.

It is to be understood that the form of this invention herewith shown and described is to be taken as a preferred example of the same, and that various changes in the shape, size, and arrangement of parts may be resorted to without departing from the spirit of the invention or the scope of the subjoined claims.

Having thus described the invention, I claim:—

1. In a device of the type described, a frame, a barrel lock actuating post journaled therein, a lateral pin carried by the post, a push bar engaging the pin to be moved longitudinally when the post is rotated in one direction and to remain in such moved position when the post is returned, a safety button having a fork slidable in a slot in the frame, a spring member for retaining the fork in the said slot and operatively connecting it to the push bar, a lever engaging said fork to be pivoted by the movement of the latter, a trigger pivoted to said frame, and a bolt operated by the lever for holding the trigger in its cocked position.

2. In a device of the type described, a frame, a barrel lock actuating post journaled therein, a lateral pin carried by the post, a push bar having a depending lug loosely engaging a side of the pin, a safety button having a fork slidable in a slot in the frame, a spring member for retaining the fork in said slot and operatively connecting it to the push bar, a lever engaging said fork to be pivoted by the movement of the latter, a trigger pivoted to said frame, and a bolt operated by the lever for holding the trigger in its cocked position.

3. In a device of the type described, a frame, a barrel lock actuating post journaled therein, a lateral pin carried by the post, a push bar having a forked end straddling the post and resting upon said pin with a depending inset lug loosely engaging a side of the pin, a safety button having a fork slidable in a slot in the frame, a spring member for retaining the fork in said slot and operatively connecting it to the push bar, a lever engaging said fork to be pivoted

120
125
130

by the movement of the latter, a trigger pivoted to said frame, and a bolt operated by the lever for holding the trigger in its cocked position.

5. In a device of the type described, a frame, a barrel lock actuating post journaled therein, a lateral pin carried by the post, a push bar having a forked end straddling the post and resting upon said pin
10 with a depending inset lug carried by one side thereof and loosely engaging a side of the pin, a finger projecting longitudinally from the opposite end of the push bar, a safety button having a fork slidable in a slot in the frame, a lateral pin carried by one side of said fork, a member having an upturned, slotted end receiving the push bar finger and having a 15 longitudinally extending slot formed in its remaining end portion for receiving the fork of the safety button for bearing downwardly against the pin carried by said safety button fork to retain the latter in said frame slot and operatively connecting the fork to the push bar, a trigger, and trigger locking means operatively connected to the safety button fork.
- 20 5. In a device of the type described, a

frame, a barrel lock actuating post journaled therein, a lateral pin carried by the post, a 25 push bar having a forked end straddling the post and resting upon said pin with a depending lug carried by one side thereof and loosely engaging a side of the pin, a finger projecting longitudinally from the opposite end of the push bar, a safety button having a fork slidable in a slot in the frame, a lateral pin carried by one side of said fork, a member having an upturned, slotted end receiving the push bar finger and having a 30 longitudinally extending slot formed in its remaining end portion for receiving the fork of the safety button for bearing downwardly against the pin carried by said safety button fork to retain the latter in said frame slot and operatively connecting the fork to the push bar, a trigger, and trigger locking means operatively connected to the safety button fork.

In testimony whereof I affix my signature.

LOUIS P. SMITH.
